228,437

PLATE OR SIMILAR ARTICLE

Marie Helene Isabella Antonia von Boch-Galhau,
3 von-Boch-Str., D-6641 Britten, Saar, Germany

Filed May 7, 1971, Ser. No. 141,457

Claims priority, application Germany Feb. 19, 1971

Term of patent 14 years

Int. Cl. D7—01

U.S. Cl. D7—32

FIG. 1 is a top plan view of a plate or similar article showing my new designs;

FIG. 2 is a side elevational view thereof;

FIG. 3 is a bottom plan view thereof;

FIG. 4 is a perspective view thereof;

FIG. 5 is an enlarged fragmentary view thereof showing a repeat portion of the design which is shaded to indicate color contrast.

The characteristic feature of the design resides in the floral pattern as shown on the upper surface of the plate.

I claim:

The ornamental design for a plate or similar article, as shown and described.
